CYRUS W. SALADEE AND WILLIAM BAUDER, OF CIRCLEVILLE, OHIO.

Letters Patent No. 86,697, dated February 9, 1869.

IMPROVEMENT IN TOP-IRONS AND PROPS FOR CARRIAGES.

The Schedule referred to in these Letters Patent and making part of the same.

To all whom it may concern:

Be it known that we, CYRUS W. SALADEE and WILLIAM BAUDER, of Circleville, State of Ohio, have invented a new and improved Mode of Constructing "Top-Irons" and "Props" for Supporting and Adjusting Carriage-Tops; and we do hereby declare that the following is a full and exact description thereof, reference being had to the accompanying drawings, and to the letters of reference marked thereon.

The nature of our invention consists, first, in a new arrangement of "props," and, in the manner of their application to the bows of the top; and, second, in a new and improved method of applying the lower "prop-iron" to the tops of carriages and buggies.

The short, T-shaped iron, known as the "prop," to which the long-jointed irons of tops are applied, are now universally secured to the outside surface of the bows, by means of four small wooden screws, and they are often torn loose by the direct strain thrown upon the seams by the straining of the top, and they are always unsightly in appearance, by reason of the fact that they must be put on the outside of the bows and top.

In the drawings, by—

Figure 1, we show a side view of these "props," S, secured to the edge of the bows E, 1, 3, and 4, by means of small wood-screws.

Figure 2 is a front view, in section, of the "prop" S, which has a square hole through its centre, through which is passed the bolt D, which also has a square next the head, in length equal to the thickness of the "prop" S, and the remaining length of the bolt is round, and which receives the ends of the "prop-irons" A and B, as shown in figs. 1 and 2.

In fig. 2, D is the bolt above mentioned, S, the "prop," through which it passes, and K is the nut, or tap, on the end of the bolt, which holds the whole arrangement together.

Our improved "top-prop," therefore, consists simply of the prop S, bolt D, and tap K, and secured to the edge of the bows E, with a loose thimble, H, figs. 2, next the prop S, as shown in the drawing.

We will here state that the bolt D may be cast solid with the prop S, and secured to the edge of the bow,

as shown, and we so contemplate manufacturing them when desired.

The prop S is first secured to the edge of the bows, as shown. The bolt D is then passed through from the inside, and the loose thimble H, fig. 2, is slipped on, after which the "prop-irons" A and B are received on the bolt.

The "quarter prop-iron" B is applied as shown in the drawing, and at or near the centre we make the joint D 1, and so as to break downward, in the direction of the dotted line 5, and to this joint D 1 we secure to the rivet or bolt of the joint, the top end of the lower "prop-iron" C.

By this arrangement, we make this lower prop-iron serve the double purpose of supporting the top, and, at the same time, to press the joint D 1 of the prop-iron B up firmly in its position, and thereby keep that portion of the leather of the top, between the bows E 3 and 4, strained tight and smooth at all times when the top is up.

To let down the top, take hold of the "lower prop-iron" C, below the joint 4, push back, when the latter joint is broken in the direction of the dotted line 6, and the joint D 1 is drawn in the direction of the dotted line 5, and the top is let back, and the two back bows are allowed to fold together as usual.

Now, what we claim as new, of our invention, and desire to secure by Letters Patent, is—

1. Securing the supports S to the edges of the bows 1, 3, and 4, and for supporting the braces B and C, constructed substantially as shown, and operating as and for the purposes set forth.
2. The combination of supports S, bolt D, and loose thimble H, substantially as described and for the purposes set forth.
3. The combination of the quarter prop-iron B, with the lower prop-iron C, constructed and operating substantially as and for the purposes set forth.

CYRUS W. SALADEE.
WM. BAUDER.
